Specification for Design.

Patented Sept. 28, 1915.

Application filed November 12, 1914. Serial No. 871,810. Term of patent 3½ years.

To all whom it may concern:

Be it known that we, LOUIS BERGMAN and JULIUS L. MENDEL, both citizens of the United States of America, and residing at New York, in the county and State of New York, have invented a new, original, and ornamental Design for Dispensing Devices, of which the following is a specification, reference being had to the accompanying drawings, forming part thereof.

Figure 1 is a side elevation, Fig. 2 a front

elevation, and Fig. 3 is a bottom plan view of a dispensing device showing our new design.

We claim:

The ornamental design for a dispensing device, as described and shown.

LOUIS BERGMAN.
JULIUS L. MENDEL.
